Emory D. Roberts, 19159 Calvert St., Reseda, Calif.

Filed Mar. 18, 1963, Ser. No. 74,004

Term of patent 14 years

(Cl. D93—3)

FIG. 1

FIG. 2

FIG. 3

FIG. 1 is a front elevational view of an expandable saw blade showing my new design;

FIG. 2 is a rear elevational view thereof; and

FIG. 3 is a side elevational view thereof.

The design for the expandable saw blade disclosed is characterized by the four saw blade sections which extend outwardly from the centrally disposed circular plate and which have the V-shaped division spaces as shown.

I claim:

The ornamental design for an expandable saw blade, as shown and described.
